C. E. MARTIN.
ROOF FOR SILOS OR THE LIKE.
APPLICATION FILED DEC. 10, 1913.

1,096,443.

Patented May 12, 1914.

UNITED STATES PATENT OFFICE.

CHARLES E. MARTIN, OF MANSFIELD, OHIO.

ROOF FOR SILOS OR THE LIKE.

1,096,443.

Specification of Letters Patent. Patented May 12, 1914.

Application filed December 10, 1913. Serial No. 805,714.

To all whom it may concern:

Be it known that I, CHARLES E. MARTIN, a citizen of the United States of America, residing at Mansfield, in the county of Rich-
5 land and State of Ohio, have invented cer-
tain new and useful Improvements in Roofs
for Silos or the like, of which the following
is a specification.

This invention relates to certain new and
10 useful improvements in roofs for silos and
the like, and the primary object thereof is
to provide a roof which is self-sustaining
and which eliminates braces or other sus-
pension means to thereby increase the hold-
15 ing capacity of the silo, by enabling the
space, usually occupied or taken up by the
roof suspension means, to be used for stor-
age of an additional amount of silage.

Further, the invention aims to provide a
20 roof which can be easily and readily assem-
bled, and which when in operative position
will provide a rigid and effective structure.

The invention consists essentially in an
approximately truncated cone-shaped body
25 which is formed in sections, the latter being
secured at their upper ends to a ring-like
part combined with a crown which is also
secured to said ring-like part in order to ef-
fectively relate the parts against movement,
30 and to also enable the structure to be easily
and quickly assembled.

In the drawings: Figure 1 is a side eleva-
tion, the door being omitted and the crown
35 of the roof partly broken away; Fig. 2 is
an interior side elevation, parts being omit-
ted and other parts being shown in frag-
ment; Fig. 3 is a fragmentary detail view
showing the manner of hinging the door;
Fig. 4 is a section taken on the line 4—4 of
40 Fig. 2; Fig. 5 is a section taken on the line
5—5 of Fig. 2; and Fig. 6 is a perspective
view of one of the brackets forming a part
of the means for securing the crown of the
roof in position.

45 The silo body 1 may be of any preferred
form and at its upper end supports the body
2 of the roof, the body 2 in turn supporting
the crown 3, which latter has a conventional
type of ventilator 4 secured thereto.

50 The body 2 of the roof is of truncated
cone-shape and is formed of a series of ta-
pered sections 4, preferably formed of cor-
rugated metal, the upper ends of which sec-
tions fit in the corner of an angle-bar ring

55 or band 5, as clearly depicted in Fig. 5 of
the drawings. Each section 4 has two or

more straps 7 secured to its upper end por-
tion on the inner face thereof, which straps
project above the extreme upper end of the
section and are bent over the angle-bar ring 60
or band so as to conform thereto, the straps
being formed of flexible or pliable material
for the purpose mentioned. The free outer
ends 8 of the straps are disposed to be en-
gaged by the free upper edges of the sec- 65
tions to which they are attached so as to
hold said ends 8 against movement, as de-
picted in Fig. 5 of the drawings. A pair
of clips 9 are secured to the inner face of
each section 4 and project below the lower 70
end of same, the clips being offset to pro-
vide shoulders or abutments 10 which seat
on the upper free edge of the body 1 so as to
thereby assist in holding the sections against
downward movement. The lower ends of 75
the clips 9 are suitably secured to the silo
body 1, by any suitable fastening means 10'.
The sides of adjacent sections overlap and
are secured together by rivets 11 or other
approved fastening means. The crown of the 80
roof is also formed of tapered sections which
are corrugated and overlap at their adjacent
sides and are secured rigidly together by
riveting, or the like. For the purpose of
rigidly connecting the crown to the body of 85
the roof, a series of hangers 12 are rigidly
secured to the under face of the crown, and
have hooks 13 borne by their lower ends,
which hooks receive and support the hori-
zontal portions 14 of brackets that have 90
their ends formed with hooks 15 which lat-
ter receive the vertical member 16 of the
angle bar ring or band 5. By this means,
the crown is rigidly secured to the roof
body and is firmly anchored in position so 95
as to resist wind and rain, etc.

A door or closure 17 is placed over the
opening 18 which latter provides access to
the interior of the silo, the lower end of the
door resting on the upper end of the body 1, 100
while its upper end has a hook shaped finger
19 secured thereto, which finger engages on
top of the ring 5 as shown in Fig. 3 of the
drawings to thereby provide a hinge connec-
tion for the door. The lower end of the roof 105
body 4 projects beyond the peripheral wall
of the silo body, and the lower end of the
crown 3, likewise extends beyond the periph-
ery of the band 5 so as to provide weather
proof joints.

In assembling a silo in accordance with
the present invention, a pair of the sections

- 4 are supported in diametrically opposed relation on the silo body 1 after which the ring or band 5 is supported from said pair of sections in the manner hereinabove described.
- 5 The remaining sections are then placed in position and secured until the roof is completely formed, space being left to provide the door opening 18 above described.
- What is claimed is:
10. 1. A silo roof including a sectional body, an angle-iron ring at the upper end of the body, the sections of the body having their upper ends engaged in the angle of the angle-iron ring, straps secured to the sections and bent around said ring, and a crown overlying the ring and secured thereto.
15. 2. A silo roof including a sectional body, an angle-iron ring at the upper end of the body, the sections of the body having their upper ends engaged in the angle of the angle-iron ring, flexible straps secured to the sections and being bent around the ring and having their free ends engaged with the upper ends of the sections, and a crown secured to the ring.
20. 3. A silo roof including a sectional body, an angle-iron ring at the upper end of the body, the sections of the body having their upper ends engaged in the angle of the angle-iron ring, flexible straps secured to the sections and being bent around the ring and having their free ends engaged between the under face of the horizontal part of the

angle-iron ring and the upper ends of the sections to thereby secure said strap ends 35 against movement, and a crown secured to the ring.

4. In a silo roof, a body member, a ring secured to the upper end thereof, a crown seating on the ring, hangers depending from 40 the crown, and brackets connected to the hangers and engaged with the ring.

5. In a silo roof, a body member, an angle-iron ring secured to the body member, a crown seating on the ring, hangers 45 depending from the crown, and brackets having central portions secured to the hangers and ends of hook-shape which engage the under edge of the vertical part of the ring.

50. 6. In a silo roof, a sectional body member, an angle-iron ring at the upper end of said member, the sections of the body member having their upper ends engaged in the angle of said angle-iron ring so that 55 the horizontal part of said ring overlies said upper ends of the sections, and a crown which seats on said horizontal part of said ring and projects therebelow.

In testimony whereof I affix my signature 60 in presence of two witnesses.

CHARLES E. MARTIN.

Witnesses:

JOHN H. COSS,
LELA RITCHIE.
